CLAIM

The ornamental design for a pipe hanger device, as shown and described.

DESCRIPTION

FIG. 1 is a perspective view of a pipe hanger device showing my new design;

FIG. 2 is a top plan view thereof;

FIG. 3 is a front elevational view thereof with the hanger shown in an extended position and the rear elevational plan view is a mirror image of said front elevational view;

FIG. 4 is a bottom plan view thereof with the hanger shown in an extended position;

FIG. 5 is a right side view thereof with the hanger shown in an extended position; and,

FIG. 6 is a left side elevational view thereof with the hanger shown in an extended position;

The broken lines showing the pipe and rod extension in FIG. 1 are for illustrative purposes only and form no part of the claimed design.
